UNITED STATES PATENT OFFICE.

SAMUEL H. HERBST, JR., OF FULLERTON, PENNSYLVANIA.

RAILWAY-TIE.

1,180,511.

specification of Letters Patent.

Patented Mar. 2, 1915.

Application filed November 9, 1914. Serial No. 871,045.

To all whom it may concern:

Be it known that I, SAMUEL H. HERBST, Jr., a citizen of the United States, and a resident of Fullerton, in the county of Lehigh and State of Pennsylvania, have invented certain new and useful Improvements in Railway-Ties, of which the following is a specification.

My invention relates to railway tracks, and one of the main objects thereof is to provide a tie for the rails which insures a resilient seat for said rails, which permits the removal of said seats for substitution or other reason without disturbing the tie itself, which is formed primarily of metal and concrete, which presents an enlarged area of tie supporting surface at its under side in the position of each rail, which provides metal reinforcing plates for the resilient means in order to prevent injury thereto, which is very simple in construction and installation, which is practically indestructible and thus insures long life, and which is comparatively inexpensive.

My invention is fully described in the following specification, of which the accompanying drawings form a part, in which like parts are designated by like reference characters in each of the views, and in which:—

Figure 1 is a plan view of my tie in operating position, and partly in section to show a detail of construction; Fig. 2 is a longitudinal, vertical, section thereof; Fig. 3 is a detached, perspective, view of a detail; and Fig. 4 is a section taken on the line 4—4 of Fig. 2.

In the drawings forming a part of this application I have shown a present preferred form of embodiment of my invention, comprising a bottom plate 5 and a parallel top plate 6 spaced therefrom by means of brackets 7 in permanent connection therewith, said upper plate 6 having a plurality of holes 8 therein to permit the passage of liquid concrete to form a central, concrete, portion 9, between, and at a distance from the rails 10. I also provide similar brackets 11 for the ends of the plates 5 and 6, but in detachable connection therewith by means of bolts 12 and nuts 13, all of said brackets being of I-formation in plan to provide projections 14 and 15, oppositely directed, from the web 16, the brackets 11 having, also, upper and lower flanges 17 and 18, respec-

tively, from the web 16, outwardly thereof, and through which pass the bolts 12.

Arranged between corresponding brackets 7 and 11 are two blocks 19 and 20, of wood or other relatively soft and resilient material, and the lower one of which, 20, is provided with a longitudinal channel 21 in the upper surface thereof, a metal filler 22 being interposed between said blocks.

The upper plate 6 is provided with openings 23 therethrough, one beneath each rail 10, and in which is arranged a wood or similar plate 24 resting upon the corresponding block 19 and extending above the plane of the upper surface of the plate 6, as clearly shown in Fig. 2, and I provide a channeled rail plate 25 for each of the wood plates 24, straddling the same, and bearing upon the corresponding block 19, and I pass one or more tie-bolts through the filler plates 22, blocks 19, wood plates 24, and rail plates 25, on each side of each rail, as shown at 26, Figs. 2 and 4, and each of which is threaded at its lower end and provided with a detachable nut 27 resting in the channel of the corresponding block 20, thus serving to hold the rails firmly in place.

If it is desired to substitute new blocks 19 or 20, or new wood plates 24, all that is necessary is to remove the bolts 12, knock out the end brackets 11, draw out the blocks 20, remove the nuts 27, and after which the tie-bolts 26 may be removed, permitting the withdrawal of the blocks 19, plates 24, and rail plates 25; new blocks or plates may now be placed in position, and the operation just described reversed to assemble the tie, and it will be seen that, not only is the tie itself not disturbed, but no considerable excavation is needed at the ends of the tie to remove the parts which it is desired to replace, this being of especial value and importance in connection with street railways in cities.

It will be observed that the rails rest upon metal, but the supports thereof are resilient, and the tie-bolts and nuts thereof bear against metal, thus avoiding the probability of either the rails or tie-bolts or nuts thereof being forced into the soft blocks or wood plates to injure the same, as is usual with the wood ties as now employed, and I therefore secure all the advantages of the said wood ties, and of metal ties, or concrete ties, and also permitting the replacing of old

wood elements or members thereof by new ones with little or no trouble, and at very low cost.

My invention is very simple, durable, 5 practical, and economical in installation and maintenance, and, while I have shown certain details of construction to illustrate the same fully and clearly, it will be understood that I do not limit myself thereto, but may 10 make changes thereover, within the scope of the following claims, without departing from the spirit of my invention, or sacrificing its advantages.

Having fully described my invention, 15 what I claim as new, and desire to secure by Letters Patent, is:—

1. The combination with the rails of a railway track, of a tie, comprising upper and lower plates, the former of which is 20 provided with an opening therethrough in the position of each rail, a resilient block for the corresponding rail projecting through each opening, a longitudinally removable block for supporting said resilient 25 block, a metal plate interposed between each rail and resilient block, a metal plate interposed between the blocks of each rail, and means for locking the respective rails, blocks, and metal plates together.
- 30 2. The combination with the rails of a railway track, of a tie, comprising upper and lower plates, brackets connecting the same and arranged between said rails, sup-

plemental brackets connecting the ends of said plates, said upper plate being provided with an opening therethrough beneath each rail, a resilient block for each rail projected through the corresponding opening and a longitudinally removable supporting block for said resilient block, said brackets being removable and serving to maintain the respective blocks in position.

3. The combination with the rails of a railway track, of a tie comprising upper and lower plates, the former of which is 45 provided with an opening beneath each rail, brackets connecting said plates, between said rails, supplemental brackets connecting said plates at the ends thereof, detachably, two superimposed resilient blocks interposed between the brackets of each pair, a metal filler plate between said blocks, a resilient plate projected through each opening and resting upon the upper block, a rail plate over said resilient plate, and 50 means for locking each rail to its rail plate, resilient plate, upper block, and filler plate, 55 detachably.

In testimony whereof I have signed my name to this specification in the presence of 60 two subscribing witnesses.

SAMUEL H. HERBST, JR.
